UNITED STATES PATENT OFFICE.

FREDERIC M. HOBLITT, OF NEW YORK, N. Y.

DESIGN FOR AN INDIVIDUAL-SEAT SERVICE-CAR BODY.

56,233.

Specification for Design.

Patented Aug. 31, 1920.

Application filed April 6, 1920. Serial No. 371,777. Term of patent 14 years.

To all whom it may concern:

Be it known that I, FREDERIC M. HOBLITT, a citizen of the United States, residing at New York, county of New York, and State of New York, have invented a new, original Design for an Individual-Seat Service-Car Body, of which the following is a specification, reference being had to the accompanying drawing, forming a part thereof, wherein:—

Figure 1 is a side view of the body showing my design and

Fig. 2 is a front view thereof.

I claim:

The ornamental design for an individual seat service car body, as shown.

Signed at New York, N. Y., this 17th day of March 1920.

FREDERIC M. HOBLITT.
